ELMER H. SMITH, OF MINNEAPOLIS, MINNESOTA

ACETYLENE-GAS GENERATOR

Application filed October 18, 1928. Serial No. 669,308.

This invention relates to improvements in acetylene gas generators and more particularly relates to improvements in such generators of the small, portable type, such as are commonly employed in manufacturing plants for generating gas for acetylene torches, etc., and are therefore frequently moved from place to place.

The particular object of the invention is 10 to provide such an apparatus having means provided therein for preventing water from entering the carbide hopper, should the generator be tilted at an angle or inverted while being transferred from one place to another.

15 A further object is to provide a generator having means for regulating and controlling the feed of the carbide into the generator tank.

The invention consists generally in the 20 constructions and combinations hereinafter set forth and particularly pointed out in the claim.

In the accompanying drawings forming part of this specification,

25 Figure 1 is a side elevation partially in section, showing a generator embodying my invention;

Figure 2 is a view showing how the generator may be placed upon its side without 30 danger of the water entering the carbide chamber;

Figure 3 is a similar view showing the generator inverted; and

Figure 4 is a sectional view showing a modified construction.

In the drawing, 2 represents the base of the tank, having the usual water chamber 3 and wall 4; the top of the generator being provided with a suitable cover 5 through which 40 access may be had to the interior. On the under side of this cover I prefer to mount a feed hopper 6 having a suitable filling opening 7 and a discharge opening 8 at its lower end. In this hopper a quantity of carbide is placed. 9 is a cone-shaped feeding member depending within the hopper and mounted on a vertical shaft 10, which projects centrally through the cover 5 and is operatively connected to a suitable spring-actuated 45 motor 11, having a crank 12 provided thereon

by means of which the motor may be wound. When the motor functions, the shaft 10 will be slowly revolved and the feeding member 9 will rotate in the feed opening 8, thus agitating the carbide and keeping it in motion sufficiently so that it will not bridge or clog in the hopper and check the normal feed. An annular space is provided between the feeding member 9 and the hopper, as shown in Figure 1, through which the carbide may 55 flow down through the discharge opening in the bottom of the hopper.

A cone-shaped valve 13 is mounted on the upper end of a rod 14 that is journaled on a crank shaft 15, having bearings in the wall 60 4 of the generator and provided with an operating crank 16. It will be observed from the dotted lines in Fig. 1 that when the valve 13 is in highest uppermost position it does not entirely close the discharge opening of 70 the hopper so that gas generated in chamber 3 may pass into the hopper as later explained. This valve 13 is for the purpose of partially shutting off the feed of the carbide, in fact, almost entirely closing the lower 75 end of the hopper, as shown by the dotted lines in Figure 1, narrow openings, however, being provided around the valve through which the gas from the tank beneath may flow upwardly through the hopper to the 80 service pipe 17. A pipe 18 depends from the hopper and encircles its discharge opening and has an open lower end through which the carbide falls into the water beneath, this pipe forming a continuation of the walls of 85 the hopper and preventing the water in the tank, when the generator is tilted, in moving it from place to place, from entering the hopper and contacting with the carbide therein.

Thus in effect, it forms a guard or shield 90 for the open lower end of the hopper, preventing the water from flowing therein when the generator is tipped down to a horizontal position or inverted, as shown in Figures 2 and 3. This pipe preferably has a cross bar 95 19 therein, which forms a guide for the rod 14, and wherein the said rod freely slides in the vertical movement of the valve 13.

In Figure 4, I have shown a modified construction which consists in providing an an- 100

nular passage 20 around the hopper communicating with the depending pipe 21 at the lower end and leading to the service pipe. In this case the gas is not passed through the hopper and the carbide, but around it, and the valve 13 may be moved upward to an entirely closed position if desired, as shown. The pipe 21 has the same function as the pipe 18 in Figure 1, and provision is also made for rotating the cone-shaped feeding member which agitates the carbide and causes it to flow downwardly through the lower end of the hopper, as previously described with reference to Figure 1.

15 I claim as my invention:

An acetylene generator comprising a closed casing, a carbide-hopper enclosed in the upper portion of the casing and having a central discharge opening, a water chamber in the lower portion of the casing, a rotatable cone-shaped feeding member located within the carbide hopper adjacent to its central discharge opening, a manually operable reciprocable rod provided with a cone-shaped valve positioned to control the discharge of carbide from the hopper, and a tubular member extending from the carbide hopper into the water chamber, said tubular member being of a diameter and length so proportioned with respect to the depth and diameter of the generating chamber as to have its lower end lie substantially midway of the length of the casing to prevent water in the chamber entering the carbide-hopper if the generator be subjected to various angular displacements.

In witness whereof, I have hereunto set my hand this 11th day of October 1923.

ELMER H. SMITH.
